UNITED STATES PATENT OFFICE.

PAUL H. ZIMMER, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTROMAGNETIC SWITCH.

1,306,874.

Specification of Letters Patent. Patented June 17, 1919.

Application filed April 23, 1914. Serial No. 833,965.

To all whom it may concern:

Be it known that I, PAUL H. ZIMMER, a citizen of the United States, residing at Milwaukee, in the county of Milwaukee and 5 State of Wisconsin, have invented new and useful Improvements in Electromagnetic Switches, of which the following is a full, clear, concise, and exact description, reference being had to the accompanying drawing, forming a part of this specification.

This invention relates to improvements in electromagnetic switches.

It has among its objects to provide an improved electromagnetic switch of the type 15 wherein the switch member is mechanically locked in attracted position to permit de-energization of its operating winding and wherein such locking means is tripped upon subsequent energization of the operating 20 winding.

The more specific objects of the invention will appear in connection with the embodiment thereof illustrated in the accompanying drawing, it being understood that various 25 modifications may be made in the structure illustrated without departure from the scope of the invention.

In the drawing,

Figure 1 is a side elevation of the switch 30 in open position and provided with certain circuit connections;

Fig. 2 is a similar view of the switch in closed position but with certain parts removed and other parts shown in section; 35 and,

Figs. 3 and 4 are detail views of a control switch for the operating magnet.

The switch includes a stationary contact 1, a coöperating movable contact 2, an electromagnet 3 and an armature member 4 for said magnet carrying the contact 2. The arrangement of parts is such that when the magnet is energized it attracts its armature 4 to move the contact 2 into engagement with 45 contact 1. On the other hand, when the magnet is deenergized its armature tends to gravitate to the position illustrated, thereby separating the switch contacts. Further, a spring 5 associated in a well-known manner 50 with the armature 4 and movable contact 2 serves to supplement the action of gravity in effecting the return of the armature and accordingly of the switch contact 2 to normal position. A latch 6 is provided to mechanically lock the armature 4 in attracted po-

sition to maintain the switch contacts in engagement and the magnet is provided with an auxiliary armature 7 to trip said latch as hereinafter set forth to effect release of the armature 4. A double-throw switch 8 is provided to be thrown in one direction by the armature 4 and in an opposite direction by the auxiliary armature 7 to effect automatic control of the circuit of the magnet 3. As hereinafter more specifically set forth, the 60 switch 8 effects deenergization of the magnet upon attraction of the armature 4 and also upon attraction of the auxiliary armature 7.

More specifically describing the structure 70 illustrated, the several parts thereof are mounted upon a suitable insulating panel or base 9. The magnet winding is arranged upon a core 10 fixed to the upright portion of an L-shaped magnet frame 11 suitably secured to the panel 9. The armature 4 is pivotally connected by a pin 12, to the outer end of the horizontal portion of the magnet frame 11 and the auxiliary armature 7 is pivotally connected, by a pin 13, to the upper 75 end of the vertical member of the magnet frame. The armatures 4 and 7 are so proportioned and arranged that when the armature 4 is in attracted position and said auxiliary armature is attracted the latter 80 will abut the extremity of the former. The auxiliary armature is, however, biased upwardly by a spring 14 connected to an adjustable device 15 on the panel 9, and this spring is so tensioned as to hold the auxiliary armature against attraction until the armature 4 is first attracted. In other words, 85 the two armatures are so arranged in the magnetic field that the auxiliary armature will be unresponsive until the armature 4 is attracted to increase the magnetic flux through said auxiliary armature to a degree sufficient to effect its attraction.

The latch 6 as best illustrated is pivoted on the pin 13 and is biased upwardly by a 90 spring 16 seated in the magnet frame and bearing against a shoulder on said latch. The free end of said latch coöperates with a roller 17 carried by the armature 4 and is provided with a notch 18, to receive said 105 roller, and thus lock said armature in attracted position. The coöperation of the latch and roller is rendered automatic by the beveled extremity 19 of said latch.

The latch 6, as aforesaid, is adapted to 110

be tripped by attraction of the auxiliary armature 7. As shown in Fig. 2, the auxiliary armature and the latch are pivoted upon the same pin and the former recessed 5 to receive the latter. Thus the armature has a portion 20 overlying said latch to strike and trip the same when said armature is attracted.

From the foregoing it will be apparent 10 that when the magnet 3 is energized it will attract its armature 4 and thereby move the contact 2 in engagement with contact 1 while the armature 4 will be locked by the latch 6. Hence if the magnet is immediately deenergized before attracting its auxiliary armature the switch will remain locked in closed position. Then if the magnet is again energized it will attract its auxiliary armature and trip the latch. This 15 in turn mechanically releases the armature 4 so that upon deenergization of the magnet said armature will return to normal position.

The switch 8 automatically effects the 20 deenergization of the magnet under the conditions just described. This switch comprises stationary contacts 21 and 22 mounted upon the panel 9 and a double throw contact 23 movable therebetween. As best illustrated in Figs. 3 and 4 the contact 23 is carried by an angular arm 24 pivoted at 25 to one end of a hollow bell crank arm 26. The arm 26 in turn is pivoted at 27 to a supporting post 28 projecting outwardly 30 from the panel 9. Adjacent to the pivotal connection between the two arms 24 and 26 the latter is provided with an insulating lug 29 to be engaged by the armature 4 and on the pivot pin of the member 26 is provided a coil spring 30 having one end bearing against the under side of the post 8 and its other end bearing against a pin 31 provided upon the arm 24, above its pivot 25. The spring 30 thus tends to hold the two 40 arms 24 and 26 in such relation that the former abuts against the latter at a point 33 and further tends to bias both arms downwardly whereby the contact 23 is normally pressed against the down contact 22. On 45 the other hand, when the armature 4 strikes the lug 29 it rocks the arm 26 against the action of the spring 30 and said spring in turn, by its engagement with the pin 31 on the arm 24, causes said latter arm to move 50 with the arm 26 until the contact 23 strikes the up contact 21. Then the spring 30 permits continued movement of the arm 26, thereby increasing the spring pressure on the contact points 23 and 21. Conversely 55 the spring 30 allows the member 24 to be depressed to break circuit between contacts 21 and 23 while the arm 26 is restrained by the armature 4. This last operation of the member 24 is adapted to be effected by the 60 auxiliary armature 7 through the medium 65

of an insulated lug 34 projecting laterally therefrom to overlie said member 24.

Thus it will be observed that the contact 23 normally stands in engagement with the down contact 22 under pressure of the 70 spring 30, that when the armature 4 is attracted it operates the arm 26 as aforesaid to throw the contact 23 into engagement with the up contact 21 and that when the auxiliary armature 7 is attracted it strikes 75 the arm 24 moving the contact 23 out of engagement with the up contact 21. Then when the armature 4 is released the arm 26 is likewise released and under the influence of the spring 30 and through its engagement 80 with the arm 24, restores the contact 23 to engagement with down contact 22. Further, it will be observed that due to the connection of the arms 24 and 26, eccentrically to the pivot of the latter, the arm 24 will, 85 in operation, receive a reciprocable, as well as oscillatory, movement, thereby providing for a wiping engagement between the contact 23 and its cooperating contacts. The advantages of this wiping contact will be 90 readily apparent.

Referring now to the circuit connections shown in Fig. 1, the magnet has one terminal connected directly to one side of a supply circuit L, L' and has its opposite terminal 95 connected to a binding post 28^a provided on the support 28 of the switch arm 8 whereby said magnet is electrically connected to said switch arm. The contacts 21 and 22 are connected through binding posts 21^a and 22^a 100 respectively to contacts s and s' respectively which are adapted to be selectively connected to line L' by a switch arm S. Thus with the parts positioned as shown in Fig. 1, engagement of the switch arm S with contact s' will complete the circuit of the magnet through switch arm 8 and contact 22. The magnet will then attract the armature 4, moving the contact 2 into engagement 105 with contact 1 and substantially simultaneously opening the control switch 8 at contact points 22 and 23 before the auxiliary armature 7 has an opportunity to respond. Also, simultaneously with the engagement of the switch contacts 1 and 2 the latch 6 will lock 110 the armature to retain the same in attracted position when the magnet is deenergized, as aforesaid. The parts will then remain in the positions described until the magnet is again energized and due to the fact that 115 the contacts 22 and 23 are separated the magnet can only be energized by shifting the switch arm S from contact s' to contact s. This will complete an energizing circuit for the magnet through contacts 23 and 21, 120 whereupon the magnet will attract the auxiliary armature 7 thereby tripping the latch 6 and at the same time moving contact 23 out of engagement with contact 21. This 125 will again effect deenergization of the mag-

net thus causing it to release both armatures 4 and 7 with the result of restoring the parts to the positions illustrated in Fig. 1.

It will, of course, be understood that the switch arm S and its coöperating contacts merely represent one of numerous control instrumentalities which might be employed to control the parallel circuits of the magnet.

What I claim as new and desire to secure 10 by Letters Patent is:

1. In combination, a switch element, mechanical means for latching the same in a certain position, an electromagnet, a member to be attracted by said electromagnet to move said switch element to said position, a second member to be attracted by said electromagnet to trip said latching means to release said switch element, the former member constituting controlling means for the magnetic circuit of said second member to insure attraction of said members progressively and means to energize and deenergize said electromagnet.

2. In combination, a switch element, mechanical means to latch said element in a certain position, an electromagnet, a member to be attracted by said electromagnet to move said switch element to said position, a second member to be attracted by said electromagnet to trip said latching means for release of said switch element, said second member having its magnetic circuit subjected to control by the former member to delay its attraction until after attraction of said former member and control means to deenergize said electromagnet automatically upon movement of said switch element to said certain position.

3. In combination, a switch element, mechanical means to latch said element in a certain position, an electromagnet, a member to be attracted by said electromagnet to move said switch element to said position, a second member to be attracted by said electromagnet to trip said latching means for release of said switch element, said second member having its magnetic circuit subjected to control by the former member to delay its attraction until after attraction of said former member and control means to deenergize said electromagnet automatically upon movement of said switch element to said certain position and also upon tripping of said latching means by said second member.

4. In combination, a switch element, mechanical means to latch said element in a certain position, an electromagnet, a member to be attracted by said electromagnet to move said switch element to said position, a second member to be attracted by said electromagnet to trip said latching means

for release of said switch element, said second member having its magnetic circuit subjected to control by the former member to delay its attraction until after attraction 65 of said former member and a double throw control switch for said electromagnet operable by certain of the aforesaid parts to insure deenergization of said electromagnet immediately upon latching and unlatching 70 of said switch element.

5. In combination, an electromagnetic winding, a main armature therefor, mechanical means for latching said armature in attracted position, an auxiliary armature 75 for said winding adapted when attracted to trip said latching means, said auxiliary armature having its magnetic circuit extending through said main armature to render its attraction dependent upon prior attraction of said main armature and means actuated by said armatures to effect deenergization of said winding substantially simultaneously with the completion of movement of each of said armatures.

6. In combination, an electromagnetic winding, a main armature therefor, mechanical means for latching said armature in attracted position, an auxiliary armature for said winding adapted when attracted 90 to trip said latching means, said auxiliary armature having its magnetic circuit extending through said main armature to render its attraction dependent upon prior attraction of said main armature and a double throw control switch for said winding operable in one direction by said main armature upon full movement thereof to deenergize said winding and operable in an opposite direction by said auxiliary armature 100 upon full movement thereof to deenergize said winding.

7. In combination, an electromagnetic winding, a main armature therefor, mechanical means to latch said armature in attracted position, an auxiliary armature for said winding adapted to be attracted thereby to trip said latching means, said auxiliary armature having attraction resistive means and having its magnetic circuit extending 105 through said main armature to render its attraction dependent upon prior attraction of said main armature and means to energize and deenergize said winding to set and trip said main armature.

In witness whereof, I have hereunto subscribed my name in the presence of two witnesses.

PAUL H. ZIMMER.
